UNITED STATES PATENT OFFICE.

JAMES W. OWEN, OF SECANE, PENNSYLVANIA, AND ALBERTIS HEWITT, OF CAMDEN, NEW JERSEY, ASSIGNORS TO VICTOR TALKING MACHINE COMPANY, A CORPORATION OF NEW JERSEY.

SOUND RECORD.

Application filed August 20, 1915, Serial No. 46,477. Renewed March 2, 1922. Serial No. 540,552.

To all whom it may concern:

Be it known that we, JAMES W. OWEN, a citizen of the United States, and a resident of Secane, in the county of Delaware, State of Pennsylvania, and ALBERTIS HEWITT, a citizen of the United States, and a resident of Camden, in the county of Camden, State of New Jersey, have invented certain new and useful Improvements in Sound Records, 10 whereof the following is a specification, reference being had to the accompanying drawings.

This invention particularly relates to commercial sound records for talking machines, 15 one of its principal objects being to provide means tending to reduce the friction between the surface of the walls of the sound record grooves and the coating stylus needle, and to thereby eliminate certain of the sibilant 20 sounds produced by the sliding frictional contact of the needle with said surfaces.

Other objects of this invention are, to provide a sound record with a smooth wear-resisting surface, and to provide a surface 25 which may be improved by the burnishing action of the stylus needle on the walls of the sound groove.

This invention comprehends a commercial sound record having a metallized wear-resisting facing, adapted to cooperate with a 30 stylus needle, to reduce the friction between said needle and record, and to thereby prevent the rapid deterioration of said needle and to prevent the needle from breaking 35 down the walls of the sound record groove.

A further object of this invention is to provide a sound record with a metallized surface which will not be detrimentally affected by expansion or contraction due to 40 the sudden temperature or atmospheric changes.

This invention, specifically stated, provides a commercial sound record having a metallized facing embedded into the record material by the impressing action of the 45 matrix or die in forming said record.

This invention further includes all of the various novel features of construction and arrangement, hereinafter more definitely 50 specified.

In the accompanying drawings, Figure 1 is a plan view of a sound record constructed in accordance with this invention; Fig. 2

is a greatly enlarged fragmentary sectional view taken on a radial transverse plane 55 coincident with the line 2—2 in Fig. 1; Fig. 3 is a fragmentary sectional view, on an enlarged scale, of a sound record tablet blank; Fig. 4 is a view similar to Fig. 3, showing the record tablet provided 60 on its upper surface with a coating of metallic powder; Fig. 5 is a fragmentary sectional view showing the coated tablet being impressed by the matrix or die, which contemporaneously forms the sound grooves in 65 the face of the record tablet and permanently embeds the metallic powder into the face thereof; Fig. 6 is a fragmentary sectional view showing the finished record, having the metallized facing embedded therein; Fig. 70 7 is a fragmentary sectional view showing a lump of record material disposed in a mold, and the matrix or die in position to impress said record material, and having its surface coated with a suitable metallic powder; Fig. 75 8 is a fragmentary sectional view showing the matrix or die impressing the record material and embedding the metallic powder into the surface thereof; and Fig. 9 is a fragmentary sectional view of the formed 80 sound record having the facing of metal, stripped from the die, embedded therein by said die.

As shown in Figs. 1 and 2, the sound record 10 has its surface, including the surface of the sound grooves 11, provided with a facing 12 of relatively frictionless wear-resisting material, preferably formed of minute metallic particles embedded in the record material and forming the walls 14 90 of said grooves 11, and providing a smooth surface formed of aluminum, copper, lead, or other soft metal or suitable substance, which will tend to resist wear by reducing the friction effected by the cooperation of 95 the stylus needle with the walls 14 of said sound grooves 11, and to consequently reduce the tendency of the stylus to produce sibilant sounds.

One process for making records of this 10 character is diagrammatically illustrated in Figs. 3 to 6, inclusive; where a record tablet blank 17, formed in any well known manner of suitable record material and providing a disc having a smooth surface, may be 10 coated, as shown in Fig. 4, with a powder

13 comprising finely comminuted metal, the particles of which are arranged to be embedded into the surface of the record material, as shown in Fig. 5, by the matrix or die 20 when impressing the grooves 11 therein, whereby the record 10, having grooves 11 provided with a metallic facing 12, as shown in Fig. 6, may be produced.

Another method for making the article 10 claimed herein is shown in Figs. 7 to 9, inclusive, where a lump 25 of suitable record material is placed in the mold 26 and the die 20 for impressing the record is provided with a thin coating 28 of gutta percha or 15 other suitable adhesive material, on its operative face, and then over this adhesive, the face of the die is provided with a thin coating or layer of suitable material, preferably of soft metal 13 in powdered form, 20 which is arranged to be embedded into the surface of said record material when said die is forced into engagement with the record material to form the record, as shown in Fig. 8, and to produce a completed record 10 25 having grooves 11 provided with a metalized facing 12, as shown in Fig. 9.

It may be here noted that a sound record having a metallic facing thus produced, not only provides a surface which is substantially 30 wear-resisting upon which the stylus needle rides, but also provides a comparatively smooth surface, which affords substantially negligible friction between the stylus and the walls of the sound record grooves, 35 which not only tends to reduce the sibilant sounds usually produced by the frictional engagement of the stylus with the walls of the sound grooves, but also materially prolongs the useful life of said record by preventing the breaking down of the walls of 40 the sound record groove as a result of continued use of the record for reproducing sound therefrom.

It may be observed that by continued use 45 of a record formed in accordance with this invention, the walls of the sound grooves will be rendered more and more smooth by the burnishing action of the needle riding thereon, and, consequently, by reason of the 50 continually decreasing friction between the needle and sound grooves, the tone producing qualities of the record will be enhanced by its use, rather than impaired.

Furthermore, it may be here stated that 55 a record thus produced, formed of the usual record material which after being pressed and cooled is rigid and unyielding with respect to the stylus of a sound reproducing machine, thus, provided with a metallic facing embedded therein in accordance with this invention, will not suffer from any sudden atmospheric or temperature changes.

It will be obvious from the above description of this invention, that the die for impressing the record may be provided with

a dermatoid metallic coating, which may be readily separable therefrom and which will adhere to the record material when impressed therein by said die, and form an integral metallic facing for said record, and therefore it is not desired to limit this invention to the precise details of construction and arrangement herein set forth, as various other modifications may be made therein without departing from the essential features of the invention as defined in the appended claims.

Having thus described our invention, we claim:

1. A sound record of suitable rigid record material, provided with a facing formed of a different material impressed therein adapted to reduce the friction between the surface of the record and a coacting stylus. 80

2. A sound record formed of suitable record material, provided with a facing of metallic particles embedded therein adapted to reduce the friction between the surface of the record and a coacting stylus. 85

3. A sound record formed of suitable record material, having a facing formed of metal in adherent relation therewith adapted to reduce the friction between the surface of the record and a coacting stylus. 90

4. A sound record formed of suitable record material, having a facing formed of metallic powder in adherent relation therewith adapted to reduce the friction between the surface of the record and a coacting stylus. 95

5. A sound record formed of suitable record material, having a facing formed of copper impressed into adherent relation therewith. 100

6. A sound record of suitable rigid material, having an impressed face of different material adapted to be burnished by the action of a stylus when used therewith. 105

7. A sound record formed of suitable rigid record material having a metallic copper face impressed therein forming a friction reducing surface. 110

8. A sound record formed of a suitable record material and a powdered metallic facing incorporated therein to form a friction reducing surface. 115

9. A sound record formed of a suitable record material having a sound record groove therein and a powdered metallic facing incorporated in the surface of the record and groove for the purposes specified. 120

10. A sound record consisting of record material rigid with respect to a stylus of a sound reproducing machine and permitting the repeated reproduction of sound therefrom, provided with a smooth rigid facing composed of material tending to reduce friction between the surface of said record and a coacting reproducing stylus. 125

11. A sound record consisting of record 130

material rigid with respect to a stylus of a sound reproducing machine and permitting repeated reproduction of sound therefrom provided with a smooth rigid facing of metal.

12. A sound record formed of suitable rigid record material having a sound record groove therein and provided with means incorporated into the surface of the record groove to reduce the friction between the coacting stylus and said groove.

13. A sound record formed of suitable record material having a sound record

groove therein and a powdered metallic facing incorporated into the surface of the record groove for the purposes specified.

14. A sound record of suitable rigid record material having a sound record groove therein, and friction reducing particles embedded in the walls of said groove, adapted to be burnished by a coacting stylus.

In witness whereof, we have hereunto set our hands this 18th day of August, A. D., 1915.

JAMES W. OWEN.
ALBERTIS HEWITT.
